UNITED STATES PATENT OFFICE.

ROSCOE G. WOLD, OF AMORITA, OKLAHOMA.

WINDMILL.

Application filed February 9, 1922. Serial No. 535,317.

To all whom it may concern:

Be it known that I, Roscoe G. Wold, a citizen of the United States, residing at Amorita, in the county of Alfalfa and State of Oklahoma, have invented certain new and useful Improvements in Windmills; and I do declare the following to be a full, clear, and exact description of the invention, such as will enable others skilled 5 in the art to which it appertains, to make and use the same.

This invention relates to an improved wind mill and one object of the invention is to provide a wind mill which is so constructed that reciprocating movement may be imparted to a vertically disposed pump shaft and at the same time permit the pump shaft to rotate with a hollow shaft through which the pump shaft extends, the pump 15 shaft imparting reciprocating movement to the pump rod of an ordinary structure of water pump and the rotating hollow shaft carrying a pulley wheel so that rotary movement may be transmitted to a driven shaft 20 at any point by means of a belt.

Another object of the invention is to so construct this wind mill that the rotating hollow shaft may carry at its upper end a carrier above which the reciprocating pump 30 shaft will extend, a rocker shaft being carried by this carrier and having connection with the pump shaft for imparting reciprocating movement to the pump shaft and the rocker shaft carrying wings which will be 35 acted upon by wind so that the rocker shaft will be rocked and at the same time the carrier and hollow shaft rotated.

Another object of the invention is to have the wings so mounted upon the outer end 40 portions of the rocker shaft that when the pump is in operation, the wind in striking one of the wings will serve to impart rocking movement to the rocker shaft and at the same time serve to impart rotary movement 45 to the carrier and hollow shaft, it being understood that when one of the wings is struck by the wind and moved to an operative position, the wings at the opposite end of the rocker shaft will be swung to an in- 50 operative position.

Another object of the invention is to provide the wings with improved blades which are pivotally mounted for movement into and out of an operative position and are normally in an operative position thus permitting the wind mill to operate whenever

the wind is blowing as long as the blades or vanes of the wings are not moved to an inoperative position.

Another object of the invention is to provide improved means for moving the vanes or blades to the inoperative position and to provide actuating means for this means which will be manually controlled and to further provide actuating means which will 60 be controlled by centrifugal force set up during rotation of the carrier and hollow shaft. By means of this actuating means which is operated by centrifugal force, the speed at which the hollow shaft and carrier rotate may be automatically controlled 65 and the shaft and carrier prevented from rotating too rapidly.

Another object of the invention is to so construct this wind mill that the rocker 70 shaft will be prevented from being rotated beyond a desired amount and thus breakage of parts prevented.

This invention is illustrated in the accompanying drawings, wherein:

Figure 1 is a view in side elevation showing the improved construction of wind mill.

Figure 2 is a top plan view with the upper end portion of the pump shaft shown in section.

Figure 3 is a sectional view taken along the line 3—3 of Fig. 2 with certain portions of the wind mill shown in elevation.

Figure 4 is a similar view taken along the line 4—4 of Fig. 2.

Figure 5 is a sectional view taken along the line 5—5 of Fig. 2.

Figure 6 is a perspective view of the manually operated actuating means for the means for moving the blades of the wings 95 to an inoperative position.

This improved wind mill will be provided with a tower construction having corner posts 1 connected by cross bars 2 and having their upper ends connected with a platform or head 3 which may if so desired be provided with a supporting ring 4 to which the corner posts 1 will be directly connected. The pump 5 is of a conventional construction and will be provided with a reciprocating pump rod 6 having vertical reciprocating movement when water is being pumped. It will also be provided with an outlet pipe 7 which may lead to a suitable storage tank or to any other point where it is desired to have the water delivered. The pump shaft 8 extends vertically through the tower and

has its lower end in swivelled connection with the pump rod 6 as shown at 9 and has its upper end extending upwardly above the platform 3 for a purpose to be hereinafter brought out. This platform 3 carries a bearing sleeve 10 through which extends a hollow shaft 11, the lower end portion of which extends through a bearing 12 and beneath this bearing 12 carries a pulley wheel 13 about which will be passed a belt 14 so that as this hollow shaft 11 rotates, rotary movement may be transmitted to the driving shaft of a machine which it is desired to operate by means of power developed by the wind mill. The upper end portion of the hollow shaft 11 is provided with an outstanding collar or bearing head 15 which is positioned above a similar head 16 at the upper end of the bearing sleeve 10. Anti-friction balls 17 will be provided between these collars so that the hollow shaft can readily rotate. It is to be understood that suitable anti-friction balls or rollers can be provided for the bearing 12 and also within the tubular bearing 10 if so desired. It will thus be seen that the hollow shaft 11 can rotate freely and it will be further seen that the pump shaft 8 which is to impart movement to the pump rod 6 may have vertical reciprocating movement and at the same time may have rotary movement with the shaft 11, this rotary movement of the shaft 8 being permitted due to the swivelled connection 9 between the shaft 8 and the pump rod 6.

An elongated carrier platform 18 is secured to the head or collar 15 at the upper end of the hollow shaft 11 and is provided at this end with upstanding bearing arms 19 which serve to mount a rocker shaft 20 which extends longitudinally of the carrier 18 with its end portions extending beyond the ends of the carrier. This carrier platform 18 is provided with an opening so that the upper end portion of the pump shaft 8 may extend upwardly through the carrier and above the rocker shaft. Arms 21 extend from this rocker shaft and are loosely connected with the lower end of a pitman link 22 which extends upwardly and has its upper end loosely connected with an arm 23 which extends from the shaft 8. From an inspection of Figs. 3 and 5, it will be readily seen that when the wind mill is in operation and the carrier platform and rocker shaft are turning in a horizontal plane, the shaft 8 and hollow shaft 11 will be rotated at the same rate of speed. It will be further noted from an inspection of these figures and Fig. 4 that as the rocker shaft rocks in a manner to be hereinafter brought out, reciprocating movement will be imparted to the pump shaft 8 while the pump shaft and hollow shaft 11 are rotating. In order to control the rocking movement of the rocker

shaft and prevent breakage due to excessive rocking movement and sudden stopping of this movement, there has been provided a bracket 24 which is secured upon the carrier 18 and extends transversely thereof. This bracket 24 is provided at its ends with upstanding bearing arms 25 with which yokes 26 are loosely connected. These yokes 26 extend inwardly and each slidably carries a stem 27 which is yieldably held against movement by means of a spring 28. An elongated collar is mounted upon the rocker shaft 20 between the arms 21 and one of the bearings 19 and is provided with spaced sections or plates 29 which are connected by a neck 30 through which a fastener 31 will pass to secure this collar upon the rocker shaft. The stems 27 are loosely mounted between the ends of the sections 29 as shown in Fig. 4 and from an inspection of this figure, it will be readily seen that when the rocker shaft is turned during operation of the wind mill, the yokes 26 will receive vertical swinging movement and the stems 27 will have longitudinal sliding movement. This longitudinal sliding movement will be retarded by the springs 28 and therefore these springs will provide brake means to prevent sudden stoppage and consequent breaking of parts.

In order to impart rotary movement to the hollow shaft and carrier, there has been provided wings upon the end portions of the rocker shaft. These wings extend at substantially right angles to each other as shown in Figs. 1 and 2 and each is provided with a frame 32 which is substantially U-shaped and has its side arms connected adjacent their free ends by a cross bar or strip 33 having openings formed therein so that fastener bolts 34 may be passed through the cross bar to secure the frame firmly against the rocker shaft. The end portions of the rocker shaft will be flattened as clearly shown so that the cross strips of the wings may be securely held in place and have no tendency towards rocking movement upon the shaft. The inner side bar of each of the frames is extended thus providing an arm extension 35 upon which will be adjustably mounted a counter-balance weight 36 so that the proper rocking movement may be easily imparted to the rocker shaft. Vanes or plates 37 are positioned between the side bars of the wings and each is provided with a pivot shaft 38. These shafts 38 are journaled in the side bars of the frame and at one side of the frame, the end portions of these shafts are bent to provide crank elements 39 upon which will be mounted a strip 40 so that the vanes or blades 37 will all turn together. One of the shafts is extended as shown at 38' and has its end portions bent to provide a lever arm 41 upon which will be mounted a weight 42. By having this

lever arm and weight, the weight will serve to normally hold the blades in the closed position. These blades have a construction similar to the slats of a window shutter and it will be readily seen that although the blades are normally held in a closed position by the weight 42, movement of the lever arm against the action of this weight will serve to move the blades or vanes to an open or inoperative position.

In order to permit of the blades being moved to an open or inoperative position when desired, to prevent operation of the wind mill, there has been provided rocker 15 shafts 43 which are mounted by means of bearings 44. Each of these rocker shafts is provided at its inner end with a depending handle element 45 and at its outer end is provided with an offset arm 46 extending for 20 engagement with the lever arms 41 when the rocker shafts are rotated to swing the arms 46 upwardly. In order to rotate the rocker shafts and swing the arms 46 upwardly, there has been provided a disk 47 which is 25 slidably mounted upon the bearing 10 and is provided with depending arms 48 which extend through openings formed in the head 3 and have their lower ends pivotally connected with the arms of a V-shaped lever 30 49. This lever 49 has its arms pivotally connected with bearings 50 carried by one of the cross bars 2 of the tower and has its outer end portions provided with an eye 51 so that a pull line 52 may be connected with 35 this lever. It will be readily seen that when the pull line 52 is drawn upon by a person standing at the foot of the tower, the lever 49 will be rocked upon the bearings 50 and the arms 48 and disk 47 will be moved upwardly. As the disk 47 moves upwardly, the rocker shaft 43 will be rotated and the arms 46 swung upwardly to engage the lever arm 41 and turn the blades 37 to an inoperative position so that the wind will not have 45 effective engagement with the wings.

It is further desired to permit the blades to be gradually opened as the wind increases in force beyond an amount which it would be safe to have the blades in the closed position. Therefore, there has been provided pendulum arms 53 which are pivotally connected with the carrier and are provided with weights 54 at their lower ends. Side arms 55 extend from the pivotally mounted 50 upper ends of the pendulum arms and extend into positions to engage the arms 46 when the arms 55 are swung upwardly. As the carrier turns with the rotating hollow shaft 11, centrifugal force will be set up as 55 the speed increases and the pendulums will swing outwardly. When the pendulums have swung outwardly a sufficient distance to bring the side arms 55 into engagement with the arms 46, the arms 46 will be swung 60 upwardly and will engage the lever arms 41

and as the speed of rotation increases, these arms 46 will be moved to swing the blades 37 towards the open or inoperative position. It will thus be seen that as the wind increases in force, the blades will be turned toward the open or inoperative position and less surface will be presented for the wind to act upon. When the blades are completely moved to an open position, the operation of the wind mill will be shut off the 70 same as when these blades are moved to the open or inoperative position by means of the disk 47 being brought into engagement with the arm 45.

When this wind mill is in operation, the 80 elements will be in the position shown in Fig. 1 with the blades shut. When the wind strikes the wings which extend downwardly, it will tend to impart rotary movement to the carrier and hollow shaft. When the second wing has swung into position for engagement by the wind, this wing which has been positioned substantially horizontally but slightly inclined downwardly will be struck by the wind and will be swung downwardly to a substantially vertical position. At the same time, the first wing will be swung to the horizontal position. It will thus be seen that as the wings swing into and out of the horizontal and vertical positions, 90 rocking movement will be imparted to the rocker shafts and at the same time rotary movement imparted to the shaft 11 and carrier. The rocker shaft is connected with the shaft 8 by means of the link or pitman 22 100 and therefore this shaft 8 will rotate with the shaft 11 but at the same time rocking movement of the rocker shaft will impart reciprocating movement to this shaft 8. The shaft 8 is connected with the pump rod 6 105 by means of the swivel connection 9 and therefore the pump rod 6 will only receive reciprocating movement so that the pump will be properly operated. It will thus be seen that by means of this wind mill, reciprocating movement may be imparted to the pump 5 to operate the same and at the same time rotary movement may be transmitted from the hollow shaft 11 by means of the belt 14. When it is desired to prevent 110 further operation of the wind mill, it is simply necessary to draw upon the pull line 52 and the disk 47 will be moved upwardly to engage the arms 45 and turn the rocker shafts 43 to swing the lever extensions or 115 lever arms 41 upwardly and thus open the shutters so that the wind cannot operate upon the wings. As previously disclosed centrifugal force set up during operation of the wind mill will have a tendency to swing 120 the pendulums 53 outwardly and thus automatically adjust the blades so that the wind mill can be prevented from turning too rapidly and breakage caused.

There has thus been provided a wind mill 130

which is very effective in operation and easy to control.

I claim:

1. In a wind mill, a supporting structure, a horizontal carrier rotatably connected with said supporting structure, a pump shaft disposed vertically in the supporting structure and having reciprocating movement, a rocker shaft carried by said carrier, means for converting rotary movement of the rocker shaft into reciprocating movement for the pump shaft, and wind operated means for rotating said carrier and during rotation thereof imparting rocking movement to the rocker shaft to reciprocate said pump shaft.
2. In a wind mill, a supporting structure, a horizontal carrier rotatably connected with said supporting structure, a pump shaft disposed vertically in the supporting structure and having reciprocating movement, a rocker shaft carried by said carrier, means for converting rotary movement of the rocker shaft into reciprocating movement for the pump shaft, and wings carried by said rocker shaft upon opposite sides of said supporting structure and placed in angular relation to each other whereby one moves upwardly to an inoperative position while the other is moved downwardly to an operative position.
3. In a wind mill, a supporting structure, a horizontal carrier rotatably connected with said supporting structure, a pump shaft disposed vertically in the supporting structure and having reciprocating movement, a rocker shaft carried by said carrier, means for converting rotary movement of the rocker shaft into reciprocating movement for the pump shaft, and wings carried by the rocker shaft for imparting rotary movement to said carrier and rocking movement to the rocker shaft, a vertical sleeve carried by and rotating with the carrier and extending axially of the carrier in the supporting structure and positioned about the pump shaft, and means for permitting transmission of rotary motion from the sleeve.
4. In a wind mill, a supporting structure, a hollow shaft disposed vertically in the supporting structure and rotatably mounted, a carrier carried by said shaft and disposed horizontally, a pump shaft extending through the hollow shaft and above the carrier, a horizontal rocker shaft carried by said carrier, wings carried by said rocker shaft for imparting rotary movement to the carrier and hollow shaft and rocking movement to the rocker shaft as the carrier rotates, and a connection between the pump shaft and the rocker shaft for imparting reciprocating movement to the pump shaft during rocking of the rocker shaft.
5. In a wind mill, a supporting structure, a horizontal carrier rotatably connected with said supporting structure, a pump

shaft disposed vertically in the supporting structure and having reciprocating movement, a rocker shaft carried by said carrier, means for converting rotary movement of the rocker shaft into reciprocating movement for the pump shaft, and wings carried by the rocker shaft for imparting rotary movement to said carrier and rocking movement to the rocker shaft, the wings having blades pivotally mounted for movement into and out of an operative position, means carried by the carrier for moving the blades to an inoperative position, manually operated actuating means for the blade moving means, and other means for actuating the blade moving means, the last mentioned actuating means being moved to an operative position by centrifugal force when the carrier is rotating.

6. The structure of claim 4 and a bearing sleeve for the hollow shaft, vanes for the wings mounted for movement into and out of an operative position and operating means for the vanes including rocker shafts extending from the wings and having lever extensions, actuating means carried by the carrier for engaging the lever extensions and rotating said rocker shafts to move the vanes to an inoperative position, and means slidably mounted upon the bearing sleeve for imparting movement to the actuating means.

7. In a wind mill, a supporting structure, a hollow shaft disposed vertically in the supporting structure and rotatably mounted, a carrier carried by said shaft and disposed horizontally, a pump shaft extending through the hollow shaft and above the carrier, a horizontal rocker shaft carried by said carrier, wings carried by said rocker shaft for imparting rotary movement to the carrier and hollow shaft and rocking movement to the rocker shaft as the carrier rotates, and a connection between the pump shaft and the rocker shaft for imparting reciprocating movement to the pump shaft during rocking of the rocker shaft, vanes for the wings mounted for movement into and out of an operative position and operating means for the vanes including rocker shafts extending from the wings and having lever extensions, actuating means carried by the carrier for engaging the lever extensions and rotating said rocker shafts to move the vanes to an inoperative position, manually operated means for imparting movement to the actuating means, and weighted arms pivotally carried by said carrier and provided with side arms for imparting movement to the actuating means when the weighted arms are swung outwardly by centrifugal force.

8. The structure of claim 1 and means for controlling rotation of the rocker shaft, said means comprising a bracket carried by

and extending transversely of the carrier and having upstanding arms, yokes carried by the arms of the bracket, a collar upon the rocker shaft, and yieldable connections 5 between the collar and yokes.

9. In a wind mill, a supporting structure, a horizontal carrier rotatably connected with said supporting structure, a pump shaft disposed vertically in the supporting 10 structure and having reciprocating movement, a rocker shaft carried by said carrier, means for converting rotary movement of the rocker shaft into reciprocating movement for the pump shaft, wings carried by 15 the rocker shaft for imparting rotary movement to said carrier and rocking movement

to the rocker shaft, the wings having blades pivotally mounted for movement into and out of an operative position, means carried by the carrier for moving the blades to 20 an inoperative position, means slidably mounted beneath the carrier for imparting movement to the blade moving means, the last mentioned means having depending rod extensions, and an operating lever 25 pivotally connected with the supporting structure and having connection with the rod extensions.

In testimony whereof I have hereunto set my hand.

ROSCOE G. WOLD.
